UNITED STATES PATENT OFFICE.

BALFOUR READ, OF MARION, INDIANA.

INTERNAL-COMBUSTION ENGINE.

1,286,409.

Specification of Letters Patent.

Patented Dec. 3, 1918.

Continuation of application Serial No. 757,308, filed March 28, 1913. This application filed November 17, 1915. Serial No. 61,877.

To all whom it may concern:

Be it known that I, BALFOUR READ, a subject of the King of Great Britain, and a citizen of the Dominion of Canada, residing 5 at Marion, in the county of Grant and State of Indiana, have invented a certain new and useful Improvement in Internal-Combustion Engines, of which the following is a full, clear, and exact description, reference be- 10 ing had to the accompanying drawings.

This invention relates to internal combustion engines, and has for its general object the improvement of devices of this type in certain matters of detail connected with 15 the design, assembling, and maintenance of the engine. More specifically the objects of the invention are the provision of new and improved means for supporting the valve lifting devices and for lubricating the same; 20 the provision of means for diminishing the noise and shock produced by the operation of the cams and valves; the provision of new and improved means for permitting the inspection and adjustment of the valve operating devices; while further objects and advantages of the invention will become apparent as the description proceeds.

Generally speaking my invention may be defined as consisting of the constructions 30 and combinations recited in the claims here- to annexed and illustrated in the drawings accompanying and forming a part of this application, wherein: Figure 1 is a longitudinal sectional view taken upon the line 35 1—1 of Fig. 2 and looking in the direction of the arrows, a portion of the cam shaft housing being shown in side elevation; Fig. 2 is a transverse sectional view of my im- 40 proved engine; Fig. 3 is a horizontal sec- tional view taken on the line 3—3 of Fig. 2 and looking downwardly; and Figs. 4 and 5 are sectional views of a modified form of my invention.

Describing the parts by reference char- 45 acter 1 represents the engine base and 2 represents generally the upper part of the engine, the base consists of a suitable sup- porting and oil containing casting. The upper part of the engine comprises a casing 50 top 3 adapted to rest upon the base or trough portion and carrying the cylinders 4 with their accountments. 5 represents the main shaft of the engine and 6 the cam shaft, the latter being located above and at one side

of the main shaft and substantially in the 55 same plane as the various inlet and outlet valves 7—7. No distinction is made between inlet and outlet valves in the present applica- 60 tion since they operate in the same way. The cam shaft is driven from the crank 65 shaft by suitable gearing such as shown at 8, and is inclosed in tight housing 10, here shown as carried by brackets or standards 11 secured to the base part of the engine in the mode described and claimed in my co- 70 pending application No. 757,308, filed March 28, 1913 of which my present application is a continuation.

In the embodiments shown in Figs. 1, 2 and 3, this housing is faced at its upper side 70 for the reception of an elongated cover mem- 75 ber 12 whose upper side is formed with a plu- rality of hollow bosses 13—13 whose upper ends open into the bottom of an elongated trough 14. In the present embodiment I have shown a four-cylinder engine with the cyl- 80 inders cast in pairs so as to leave room for a center bearing, wherefore I have formed the covering 12 in two parts, one for each end of the cam trough. One of the bosses 85 13 is located in alignment with each valve stem 15.

Slidably mounted in each boss is a rod 16, each of which has its lower end formed to coöperate with one of the cams 17 car- 85 ried by the shaft 6. In the present em- bodiment these rods are shown as provided with mushroom heads 18, although it is ob- 90 vious that rollers or the like could equally as well be employed. These rods are ar- 95 ranged one in line with each of the valve stems 15, and the upper end of each of the rods is provided with an adjustable ex- 100 tension 19 whereby the lifting of the valve may be adjusted. The upper surface of this extension is always located below the top of the trough 14, and the bottom of the trough is placed in constant communication with the interior of the housing 10 by means of suitable ducts 20 formed in the bosses 13. 100

Associated with the engine is the usual oil pump 22, here shown as of the rotary type and driven by the shaft 23 which in turn is operated from the cam shaft 6 through the agency of suitable gearing. This oil 105 pump is connected by means of ducts 24 with the housing 10 so that the oil from the pump will be delivered under pressure to

- the interior of the housing; a part of the same passing by way of the oil tubes 25 to different parts of the engine which require lubrication and the remainder passing by way of the ducts 20, to the troughs 14 and overflowing again into the interior of the crank casing. The housing 10 thus takes the place of the usual header or manifold from which the oil tubes start.
- 10 The valves are closed by the springs 26 pressing against fixed washers 27, and the throw of the cams is made greater than the lift of the valves, the jump rods being of such a length as to have a slight longitudinal movement when the valve is closed. The pressure of the oil in said housing serves to maintain the jump rods in close contact with the valve stems when the valves are closed, but without impeding such closing movement. The submersion of the cams in the oil prevents the occurrence of any audible blow when the elevated portion thereof comes in contact with the jump rods, the pressure of the oil serving to interpose a cushion of the same between the cam and jump rod at all engine speeds. The length of the housing 10 being less than that of the crank casing permits this housing, together with the cam shaft, cams, rods, etc., to be assembled in a convenient and efficient manner and the upper part of the engine applied to the base part after the completion of this assembly, whereupon it will immediately be ready to run. I have shown each trough as formed with a removable side 29 adapted to be held in place by the thumb nut 30, thus permitting easy access to the upper ends of the rods as may be necessary to adjust their length.
- 40 In Figs. 4 and 5 I have illustrated a slightly modified form of my invention wherein the oil cups of the different valve lifters are wholly separate from each other. In these views the cylinders, crank shaft, cam shaft, valves, stems and lifting rods carry the same numerals as before, but the top of the housing 10^a, instead of being faced for the reception of a cover member, is formed with a plurality of apertures 35 for the reception of bearing sleeves 37—37 in which the rods 16 are slidably supported. The sleeves 37 are arranged, one in line with each of the valve stems 15, and the upper end of each sleeve is surmounted by an open cup 38, the bottom whereof is placed in constant communication with the interior of the housing by means of a duct formed in each sleeve. The sides of the housing 10^a may, if desired, be made integral, but are preferably, as here shown, formed with removable plates 40 permitting access to the interior for purposes of inspection, cleaning, and repairing. The oil cups surrounding the upper ends of the jump rods are not essential, since the maintenance of pressure in-

side the housing prevents the separation of the jump rods and valve stems at this point. In fact such cups in the absence of a closed housing and an oil pressure therein are of very little efficiency at high engine speeds, 70 since the oil does not have sufficient time to enter the space between these members. For example, in an engine running 2500 revolutions per minute or over 40 revolutions per second, which is not at all an excessive speed 75 under present day automobile practice, the length of time during which a possible separation exists is less than 1/30th of a second, which is not sufficient to permit the formation of a cushioning film between the 80 parts in an open oil cup, although the pressure existing inside the housing combined with the rolling movement of the cam will sweep a film of oil between the cam face and the jump rod.

85 While I have necessarily described my invention in detail I do not propose to be limited thereby, except as the same may be positively included in the claims hereto annexed or rendered necessary by the state of 90 the prior art.

Having thus described my invention, what I claim is:—

1. In an internal combustion engine, the combination, with cylinders and reciprocable valves for said cylinders, of a cam shaft at one side of said cylinders, a housing enclosing said cam shaft, cams carried by said shaft, valve operating members projecting into said housing and extending into proximity to said cams, an oil pump, connections between said oil pump and the interior of said housing, a cup surrounding the point of contact between each valve operating member and its valve stem, and means for conveying oil from the interior of said housing to each of said cups. 95

2. In an internal combustion engine, the combination with cylinders and reciprocable valves for said cylinders, said valves being provided with stems and closing springs, of a hollow housing, a cam shaft in said housing, reciprocable members sleeved in the wall of said housing and coöperating with said cams, said members being also operatively related to said valve stems and adapted to open the same against the pressure of said closing springs, and means for maintaining said housing full of oil under pressure, the throw of said cams being 110 greater than the displacement of said valve stems. 115

3. In internal combustion engines, the combination with cylinders and cylinder valves, said valves having substantially vertical stems, and closing springs whereby said stems are depressed, of containers surrounding the lower ends of said valve stems, reciprocable means within said containers and separated therefrom; said means being 125 130

adapted to engage the ends of the said stems, mechanism for actuating said reciprocable means whereby said valves may be opened against the pressure of said spring, the 5 length of reciprocation of said means being greater than that of said stems, and means for maintaining said containers filled with oil.

4. In internal combustion engines, the 10 combination with cylinders and cylinder valves, said valves having substantially vertical stems, and closing springs whereby said stems are depressed, of a cam shaft below said stems, a housing inclosing said cam 15 shaft, cams on said shaft within said housing, jump rods sleeved in the side of said housing and having their upper ends in alinement with said stems and their lower ends in proximity to said cams, containers 20 surrounding the points of engagement of said stems and rods, an oil pump, connections between said oil pump and housing whereby said housing is maintained full of oil, and means for transferring oil from 25 said housing to said containers.

5. In internal combustion engines, the combination with a cylinder and its valves, said valves having substantially vertical stems and closing springs whereby said 30 stems are depressed, of a housing at one side of said cylinder, bearings in said housing, a cam shaft journaled in said bearings, cams carried by said shaft within said housing, sleeves carried by said housing, reciprocable rods in said sleeves and having their upper ends in alinement with said stems and their lower ends in proximity to said cams, a container carried by said sleeves and surrounding the points of engagement of said 35 stems and rods, an oil pump and connections between said oil pump and housing whereby said housing is maintained full of oil, said sleeves being formed with ducts for transferring oil from said housing to said container.

6. In an internal combustion engine, the combination with a split crank case having cylinders carried by one part of the same and a crank shaft journaled in the other 50 part, the plane of separation of said crank case parts being substantially horizontal, of an inclosed elongated housing carried by the lower half of said case and projecting upwardly into the upper half of the same, a lay shaft journaled in said housing, driving connections between said crank shaft and lay shaft, an oil pump communicating with the lower half of said casing, a shaft for said pump substantially transverse to said 55 lay shaft, means for driving said pump shaft, oil supply connections between said pump and said housing, cams carried by said lay shaft within said housing, and valve lifting devices coöperating with said 60 cams.

7. In an internal combustion engine of the puppet valve type the combination with a valve stem, of a hollow housing, a cam shaft in said housing, a jump rod sleeved in the wall of said housing in alinement 70 with said valve stem and adapted to coöperate with said cam, and means for maintaining said housing full of oil under pressure, the throw of said cam being greater than the lift of the valve. 75

8. In an internal combustion engine, the combination with cylinders and reciprocable valves for said cylinders, said valves having stems and closing springs, of a cam shaft, a hollow oil tight housing surrounding said 80 cam shaft, a plurality of reciprocable valve operating elements slidably mounted in the wall of said housing in alinement with the valve stems but independent thereof, a cam carried by said shaft in operative relation 85 to each of said members, and a pressure pump operatively connected to said housing and adapted to maintain the same full of oil under pressure.

9. In an internal combustion engine, the 90 combination, with cylinders and reciprocable valves for said cylinders, said valves having stems, of reciprocable members mounted in alinement with the valve stems, cams for operating said reciprocable members, the 95 possible displacement of said reciprocable members being greater than that of said valves, a housing carried by the engine frame and surrounding said cams and the ends of said members coöperating therewith, and means for supplying liquid under pressure to said housing. 100

10. In an internal combustion engine, the combination of a valve having a reciprocable stem, a reciprocable valve operating member spaced therefrom, the ends of said stem and member being complementarily surfaced, means for reciprocating said valve operating member, an oil pump driven by the engine, and an oil duct leading from 105 said pump to a point adjacent to the meeting ends of said member and stem whereby a continuous supply of fluid may be maintained between them.

11. In an internal combustion engine, the 115 combination with cylinders and reciprocable valves for said cylinders, said valves being provided with stems and closing springs, of a closed housing carried by the crank casing, a cam shaft journaled within said housing, 120 reciprocable members mounted in the wall of said housing in alinement with said valve stems and adapted to open the same against the pressure of said closing springs, the displacement of said reciprocable members 125 being greater than that of said valves and the meeting ends of said members and stems being complementarily surfaced, an oil pump driven by the engine, connections between said oil pump and the interior of said 130

housing, and means for conveying oil from the interior of said housing to said complementarily formed surfaces.

12. In an internal combustion engine, the combination with cylinders and cylinder valves, said valves having substantially vertical stems and closing springs whereby said stems are depressed, of a housing below said stems, jump rods sleeved in the side of said housing and having their upper ends in alinement in said stems, means for reciprocating said jump rods, the displacement of said rods being greater than that of the valve and the meeting ends of said rods and stems being complementarily surfaced, an oil pump, connections between said oil pump and housing whereby said housing is maintained full of oil, and means for transferring oil from said housing to said meeting surfaces.

13. In an internal combustion engine, the combination of a valve having a reciprocable stem, a hollow housing opposite said stem, a reciprocable valve operating member slidably sleeved in the wall of said hous-

ing and adapted to engage said stem, means for reciprocating said member, and an oil pump driven by the engine and connected to said housing whereby the same is kept full of oil under pressure.

14. In an internal combustion engine, the combination of a valve having a reciprocable stem, a hollow housing opposite said stem, a reciprocable valve operating member sleeved in the wall of said housing and adapted to engage said stem, means for reciprocating said valve operating member, an oil pump driven by the engine whereby said housing is maintained full of oil under pressure, and an oil passage along said stem leading from said housing to a point adjacent the meeting ends of said stem and member.

In testimony whereof, I hereunto affix my signature in the presence of two witnesses.

BALFOUR READ.
